UNITED STATES PATENT OFFICE

FRANK C. MARQUARDT, OF BROOKLYN, NEW YORK, ASSIGNOR TO AMERICAN BANK
NOTE COMPANY, OF NEW YORK, N. Y., A CORPORATION OF NEW YORK

DATING ATTACHMENT FOR ROTARY PRINTING MACHINES

Application filed July 12, 1928. Serial No. 292,255.

My invention relates to dating attachments for rotary printing machines, and more particularly to a mechanism operating entirely independently of a plate cylinder and including therein adjustable types of limited area 5 and means for inking same.

In multicolor work, even though the impressions be made upon dry paper, it is desirable, particularly with high grade work, 10 to allow a considerable interval between the making of succeeding impressions upon the sheets to ensure a complete drying or oxidizing of the ink so as to secure uniformly perfect complete imprints.

Heretofore, in such work, there has been 15 no certainty of the time intervals between different impressions, manufacturing methods having been more or less hit or miss.

With the above conditions in mind, I have 20 provided an attachment for use with multicolor offset planographic printing presses, by means of which each sheet will have impressed thereon, data indicating the time of the making of the impression upon that particular sheet, so that succeeding impressions 25 may be made in the same progression as the preceding impressions and thus ensure substantial uniformity in the conditioning of all sheets while in process. It is feasible 30 to utilize this mechanism as a means of identifying the press upon which the preceding impression was made, in addition to the time of the making of this impression, either by 35 the color of the date imprint or by some individual marking.

The dating attachment above referred to 40 comprises a mechanism associated with the inking mechanism of one of the plate cylinders and including therein a wheel or wheels 45 adapted to each receive a dater head for impressing upon the offset blanket of the transfer cylinder matter indicating the date on which the machine made certain impressions. This mechanism is so constructed that it may 50 be set with considerable nicety in relation to the planographic offset cylinder, and is so incorporated in the printing machine that it may be used or not as desired. One or more wheels, each carrying a dater head, may be 55 incorporated in the attachment, and each

wheel is capable of being so set as to ensure accuracy of the placing of the imprint made therefrom upon the blanket of the offset cylinder, thus adapting the device for use in connection with the printing of sheets of different sizes or bearing different designs thereon, 55 it being understood that the impression made as a result of the use of this mechanism is merely for the purpose of identification of the sheet as a whole and is not a part of the final imprint or imprints. In fact the identifying marks are usually placed closely adjacent one edge of each sheet so that they will be removed when trimming the sheets.

For inking the types of the dater head, I 60 utilize an inking mechanism including an inking roller co-operating with the inking mechanism of the plate cylinder adjacent which the dater mechanism is mounted. This inking mechanism is supported upon 65 the same carriage as the distributing and inking rollers co-operating with the plate upon the plate cylinder so that with the actuation of the throwoff mechanism operative upon such inking roller carriage, the dater inking 70 mechanism will also be thrown out. Said inking mechanism is also so constructed that it may be made inoperative in relation to the dater wheel or wheels entirely independently 75 of the actuation of the throwoff mechanism operative upon the inking mechanism with which it is associated.

I also provide means whereby the rollers 80 of the inking mechanism for the dater wheel or wheels may be adjusted in relation to the plate cylinder inking mechanism and to the dater wheel, and entirely independently of the plate inking mechanism adjustment.

The invention consists primarily in a dating attachment for rotary printing machines 90 embodying therein a wheel mounted adjacent the printing cylinder and the inking mechanism of a plate cylinder co-operating therewith, means for rotating said wheel, means whereby a dater head may be mounted 95 upon said wheel, and an inking roller in engaging relation with the inking mechanism of the plate cylinder and said wheel, and in such other novel features of construction and combination of parts, as are hereinafter 100

set forth and described, and more particularly pointed out in the claims hereto appended.

Referring to the drawings,

5 Fig. 1 is an end view of a dater attachment embodying the invention showing a fragmentary portion of the printing cylinder and associated plate cylinder, and the inking mechanism for the latter; and

10 Fig. 2 is an end view showing one of the wheel units and its associated parts at one side of the press.

Like numerals refer to like parts in both of said views.

15 In the embodiment of the invention shown in the drawings, 10 indicates the printing cylinder of an offset printing machine having the usual rubber blanket 11.

Associated with this cylinder 10 is a plate cylinder 12 provided with the usual plate 13 for impressing a design in one or more colors upon the blanket 11.

20 Associated with the cylinder 12 is an inking mechanism including inking rollers 14, distributing rollers 15 and other parts not shown in the drawings.

Associated with one of the inking rollers 14 is a vibrator roll 16 of a construction usual and well known with printing machines 25 of the type to which my invention relates, this vibrator roll working the ink upon, and picking up ink from, the upper inking roller 14. Each arbor of the vibrator roll 16 is mounted in a bearing bracket 17 carried by 30 a stud 18 secured to the side frame of the machine.

35 It will be understood that the various cylinders, shafts and rollers heretofore, and to be hereinafter, referred to, extend from side frame to side frame of the machine, and that the various parts supporting and actuating same are duplicated adjacent said side frames.

40 In the accompanying drawings, the dater attachment is located adjacent and below the feed shelf of the machine, (not shown) which location is a matter of convenience since it permits accessibility to the mechanism for the purpose of setting the adjustable type 45 members and cleaning same, as well as the adjustment of the attachment for the proper locating of the imprint therefrom, in relation to the imprint or transferred design from the cylinder 12.

50 This attachment comprises a shaft 19 mounted at each end in a bearing link 20, pivoted upon the main frame of the machine below the feed shelf.

55 Acting upon each link 20 is a spring rod 21, having a normal tendency to force the link and the shaft toward the impression cylinder 10.

60 Carried by the shaft 19 is a wheel or wheels 22 provided with clamping means 23, by

means of which an ordinary dater head 24 may be secured to the wheel.

This dater head need not be described in detail since it is of the usual and well known construction common in what is known as hand dating machines, and consists merely of a frame having a plurality of wheels therein bearing different months of the year, digits by which the days of the month may be indicated and different years. The latter, if desired, may be dispensed with since the year is no great factor as to the printing of sheets, the completion of which will occur in days. Year indicia, however, may be used if desired.

65 The shaft 19 is rotated from the gear 25 of the cylinder 10, through the gear 26 carried by said shaft. The ratio of the wheel 22 to the cylinder 10, and of the gear 26 to the gear 25 is as 1 to 4, since the cylinder 10 is a double blanketed cylinder capable of making two impressions with each revolution thereof, and the blankets are so spaced apart as to permit this ratio. The proportions of the wheel must be such that the types carried thereby will reach the printing position only once during the transfer of the ink design upon the blanket 11, and will be accurately timed with relation to the cylinder 10 so as to always make the imprint at a predetermined point of the blanket or both blankets, in the event of the use of two blankets upon said cylinder.

70 Also carried by and rotatable with the shaft 19 is a bearing disk 27 adapted to engage an end bearing disk 28 of the cylinder 10. This bearing disk will avoid the possible development of overpressure of the dater head wheels against the blanket 11. Other means, however, are provided by which accurate adjustment of the relation of said wheels to said blanket may be secured, such as an adjustable stop screw 29 carried by the bearing link 20 and acting against a stop stud 30 carried by the side frame of the machine. The dater head wheel 22 is mounted upon the shaft 19 by means of set screws 31 and 32, so that this wheel may be adjusted either circumferentially or axially of the shaft 19 to permit the proper timing of the transfer of the ink design from the dater head to the blanket 11, or to properly position said wheel in relation to the transferred ink design upon the blanket so as to secure a desired positioning of the imprint upon the printed sheet.

75 Both of these adjustments are to compensate for necessary variance in the place of the imprint due to imprints of different sizes or dimensions. Considerable nicety in both 80 adjustments may be required, although ordinarily there is sufficient margin allowed on the printed sheets, to afford ample space for the date imprint in a position where, with the trimming of the sheets, it will be removed from any of the complete imprints. The ad-

130

justment axially of the shaft is made necessary in a machine of the type in connection with which the invention is shown, by the construction of the inking rollers, associated with the plate cylinder 12. Of course, if a continuous vibrator roll 16 were to extend, entirely across the machine, the wheel 22 could be set anywhere between the side frames. But where the vibrator roll is cut up into a series of spaced narrow sections, it is obvious that the setting of the wheel 22 must be such as to utilize one of these sections as a source of ink for the wheels of the dater head 24.

15 The actual inking of the wheels of the dater head 24 is by a narrow inking roller 33 mounted in an arm 34, pivotally mounted upon a tie rod 35 extending from side to side of the carriage for the inking mechanism associated with the cylinder 12. The tie rod 35 is stationary, and the arm 34 is adjustable along this rod, since it is secured thereto by means of a split collar 36.

20 The arm 34 is of a length to bring the roller 33 intermediate the vibrator roll 16 and the wheel 22. It is necessary, however, to provide for a right angular adjustment of this roller in order to cause it to be positioned where it will engage and develop the proper 25 pressure in relation to both the roller 16 and the dater wheels. To secure such an adjustment, I mount the roller in a slide shown in dotted lines at 37, in the head of the arm 34, this slide carrying a set screw 38 and a lock 30 nut 39, thus permitting adjustment of said 35 roller 33 in a substantially horizontal line.

Carried by the arm 34 and acting against a stop 40 carried by the shaft 35, is a set 40 screw 41 provided with a lock nut 42, by means of which the arm 34 may be pivotally 45 adjusted, the vertical component of this adjustment serving to allow a desired vertical movement of said roller 33. At the same time, the horizontal component of this pivotal 50 adjustment will disturb the adjustment secured through the set screw 38, so that the adjustment of the roller 33 can be secured only by the utilization of both adjusting screws 38 and 41.

55 The stop 40 limits the movement of the arm 34 toward the wheel 22, and opposite thereto is a second stop 43 also engageable by the screw 41 for limiting the movement of the arm 34 in the opposite direction when it is desired to throw the roller 33 out of the operative 60 relation, as when it is not desired to use the dater. This may occur during the makeready of the press or with certain classes of work.

65 The split collar 36 may be set sufficiently tightly upon the shaft 35 to permit movement of the arm 34 with the application of a little force thereto, or if desired the clamp collar 36 may be so tightly set as to require its 70 partial release to permit such turning move-

ment. The length and weight of the arm, however, is sufficient to permit the collar 36 to be set fairly loosely, merely enough friction being required to prevent displacement thereof as a result of the action or movement of the shaft carrying the vibrator roll 16.

75 The operation of the herein described attachment is substantially as follows:—

An attachment of the character herein described, in addition to its independent functioning, must conform with the conditions about the press in connection with which it is used, and must be so constructed and arranged that it will not interfere with the 80 cleaning of the press upon the completion of a run, or with its makeready preparatory thereto.

85 The only work ordinarily required during the makeready of the press is upon the plate cylinders, and during a trial run for the purpose of adjusting the press for register and securing a proper initial inking of the plates. While this work is being done, it is desirable to move the wheels 22 so as to bring the dater head out of pressure relation 90 to the blanket 11. This is done by means of the adjusting screw or screws 29 which, when turned in one direction, will move the links 20 against the tension of the spring rod 21 so as to move the shaft 19 away from the 95 planographic cylinder 10.

100 While such movement of said wheel 22 has a tendency to rock the arm 34, it is preferable to move the inking roller 33 from the roll 16 and the wheel 22 prior to this adjusting of the wheel. If the frame supporting the inking rollers 14, 15 and 16 be moved so as to disengage them from the plate 13, no movement of the arms 34 is necessary since the rod 35 will have movement with the frames and 105 will thus position the inking roller 33 so as to disengage it from the dater head carried by the wheel 22.

110 When the press is ready for a run, the adjusting screw 29 may be withdrawn to an extent to permit engagement of the bearing wheel 27 with the bearing plate 28 of the cylinder 10, it being possible to secure extreme nicety in the relation of the dater head types with the blanket 11 by a minute adjustment of said screw.

115 The spring rod 21 will maintain the proper relation of the wheel 22 and the cylinder 10.

120 The operative moment of the dater head may be predetermined by a circumferential adjustment of the wheel 22 upon the shaft 19. The screw 29 may be utilized to position the shaft 19 so as to permit a free turning movement of the wheel upon said shaft, the gear 26 preventing the turning of the shaft during this adjustment of the wheel. By turning the wheel, the imprint from the dater head types may be positioned at the margin adjacent the forward or the rear edge, or at any 125 130

point along the side margin, of the sheet, if space is available along this side margin.

It is desired to position the date imprint at some particular point intermediate the edges of the sheet, the wheel may be adjusted axially of the shaft 19, provided that there is available at that point, a vibrator roll section from which ink may be picked up for use in inking the dater head. When the wheel 22 is moved axially of the shaft 19 it is also necessary to move the arm 34 axially of the rod 35 so as to secure a proper co-operating relation between the inking roller 33 and the dater head upon said wheel 22. It is also necessary to move the arms 40 and 43 with the arm 34. Since the vibrator roll 16 is primarily provided to coact with the inking roller 14, axial adjustment of this vibrator roll is impossible.

20 It is customary, however, in a printing press of the type in connection with which the invention is illustrated, to use a number of narrow vibrator rolls positioned at spaced distances along the shaft carrying the roll 16 25 so that the inking roller 33 may be positioned within the operative range of any of these vibrator sections. Of course it is possible, with some classes of work, to use a continuous vibrator roll, and when such is the case, no restrictions are placed upon the extent of axial adjustment of the wheel 22 and the parts co-operating therewith.

When the wheel, the inking roller and other co-operating parts have been properly adjusted in relation to the cylinder 10 and to the vibrator roll, the links 20 may be adjusted so as to ensure the proper engagement of the wheels of the dater head 24 with the blanket 11, and the arm 34 may be restored to its normal position as shown in Fig. 1, where it will 40 pick up ink from a vibrator roll 16 and transfer it to the dater wheels.

If there is not a proper inking operation by the roller 33 either as a result of an improper engagement therewith of the vibrator roll or with the dater head, the roller 33 may be adjusted in relation to the arm 34 and roll 16 by means of the adjusting screws 38 and 41. By moving the screw 41 toward or from the arm 40, the roller 33 will be moved in an upward or downward arc from or toward the vibrator roll 16 and the wheel 22. By means of the screw 38, the roller 33 may be moved substantially horizontally toward or from said roll and said wheel. By the alternate use of said screws 38 and 41, the roller 33 may be universally adjusted so as to accurately engage both the roll 16 and the dater head wheels.

60 When the foregoing adjustments have been made, power may be applied to the machine, and with each rotation of the wheel 22 the dater head wheels will be inked and the characters thereon will be transferred in ink to the 65 blanket 11 at a point where an impression will

be made in the desired marginal position upon the printed sheet. There being two blankets upon the cylinder 10, the date will be transferred to each of these blankets in the same position. With a ratio of 1 to 4 70 between the gear 25 and the gear 26 the two blankets upon the cylinder will be diametrically opposite each other and will be spaced apart. These blankets ordinarily each extend through 90° of the surface of the cylinder 75 10, and are spaced apart approximately 90°. This will ensure the imprints of the dater wheels 24 appearing in the same position upon each blanket and cause an imprint to be made only upon every other revolution 80 of the wheels 22, the dater wheels reaching the printing position during one revolution of the wheels 22 between the blankets. The roll 16, in addition to cutting ink upon the roller 14, will transfer ink to the roller 33 85 which will apply it to the dater wheels.

While the amount of ink used will be very small, this is of little or no importance as the quality of the impression made by the dater head is limited merely to legibility.

90 Where wide sheets are to be printed, it is possible to use any desired number of wheels 22 so that the date impression will appear upon each sheet in the event of the cutting of large sheets into smaller ones preparatory 95 to their run upon another machine. The possibility of adjustment of the wheels 22 so as to cause the imprint to be upon either the forward, rear or side margins will permit the cutting of the sheet both longitudinally and transversely and still have each portion bear the date of the imprint of the background tint.

100 The dater head wheels are set by hand and their position is not changed during the run of the press.

In machines of the type to which my invention relates, ink applied by the rollers 14 may be in isolated or adjoining stripes and of different colors, in which case the vibrator roll 110 ordinarily will be made up of spaced sections as heretofore referred to, or only one color may be used throughout the length of the said rollers 14, in which case a continuous vibrator roll may be used. In the first instance, by locating the wheel 22 with 115 relation to a section of the vibrator roll having a particular color upon one press and locating it upon another press so as to have it inked in another color, it is possible to identify the press upon which the sheets were printed by the color of the imprint.

120 The construction and location of the dater mechanism is such as to permit substantially the same degree of accessibility to the planographic offset cylinder as though the press were not equipped therewith. The location of the attachment, however, is not material to the invention considered in its broader aspects.

In actual practice it has been found that the use of an attachment as herein described greatly facilitates the orderly progress of work in production and affords a check upon different departments. It also guards against the premature making of succeeding impressions inasmuch as approximately the elapsed time between impressions may be determined by the various employees handling the paper between the making of the first impression and the delivery of the tinted sheets for the making of the succeeding impression.

It is not my intention to limit the invention to the precise details of construction shown in the drawings, it being apparent that such may be varied without departing from the spirit and scope of the invention.

Having described the invention, what I claim as new and desire to have protected by Letters Patent, is:—

1. A dating attachment for rotary printing machines embodying therein a wheel mounted adjacent the printing cylinder and the inking mechanism of a plate cylinder co-operating therewith, means for rotating said wheel, means whereby a dater head may be mounted upon said wheel, and an inking roller in engaging relation with the inking mechanism of the plate cylinder and said wheel.

2. A dating attachment for rotary printing machines embodying therein a wheel mounted adjacent the printing cylinder and the inking mechanism of a plate cylinder co-operating therewith, means for rotating said wheel, means whereby a dater head may be mounted upon said wheel, means whereby said wheel may be adjusted circumferentially to vary the operative moment of said dater head in relation to the printing cylinder, and an inking roller in engaging relation with the inking mechanism of the plate cylinder and said wheel.

45 3. A dating attachment for rotary printing machines embodying therein a wheel mounted adjacent the printing cylinder and the inking mechanism of a plate cylinder co-operating therewith, means for rotating said wheel, means whereby a dater head may be mounted upon said wheel, means whereby said wheel may be axially adjusted to secure a desired position of the imprint of the dater head upon said printing cylinder, and an inking roller in engaging relation with the inking mechanism of the plate cylinder and said wheel.

60 4. A dating attachment for rotary printing machines embodying therein a wheel mounted adjacent the printing cylinder and the inking mechanism of a plate cylinder co-operating therewith, means for rotating said wheel, means whereby a dater head may be mounted upon said wheel, means whereby said wheel may be adjusted circumferentially

to vary the operative moment of said dater head in relation to the printing cylinder, means whereby said wheel may be axially adjusted to secure a desired position of the imprint of the dater head upon said printing cylinder, and an inking roller in engaging relation with the inking mechanism of the plate cylinder and said wheel.

5. A dating attachment for rotary printing machines embodying therein links pivotally mounted adjacent the printing cylinder and the inking mechanism of a plate cylinder co-operating therewith, a shaft mounted in said links, a wheel carried by said shaft, means normally forcing said links toward said cylinder, means for limiting movement of said links toward said cylinder, a gear carried by said shaft enmeshed with a gear upon said cylinder, means whereby a dater head may be mounted upon said wheel, and an inking roller in engaging relation with the inking mechanism of the plate cylinder and said wheel.

6. A dating attachment for rotary printing machines embodying therein links pivotally mounted adjacent the printing cylinder and the inking mechanism of a plate cylinder co-operating therewith, a shaft mounted in said links, a wheel carried by said shaft, means normally forcing said links toward said cylinder, means for limiting movement of said links toward said cylinder; adjustable means whereby said links may be moved and maintained away from, or permitted to move toward, said printing cylinder, a gear carried by said shaft enmeshed with a gear upon said cylinder, means whereby a dater head may be mounted upon said wheel, and an inking roller in engaging relation with the inking mechanism of the plate cylinder and said wheel.

7. A dating attachment for rotary printing machines embodying therein links pivotally mounted adjacent the printing cylinder and the inking mechanism of a plate cylinder co-operating therewith, a shaft mounted in said links, a wheel carried by said shaft, means whereby said wheel may be adjusted circumferentially of said shaft to vary the moment of the making of the imprint from a dater head carried by said wheel upon said printing cylinder, means normally forcing said links toward said cylinder, means for limiting movement of said links toward said cylinder, a gear carried by said shaft enmeshed with a gear upon said cylinder, means whereby a dater head may be mounted upon said wheel, and an inking roller in engaging relation with the inking mechanism of the plate cylinder and said wheel.

8. A dating attachment for rotary printing machines embodying therein links pivotally mounted adjacent the printing cylinder and the inking mechanism of a plate cylinder co-operating therewith, a shaft mount-

ed in said links, a wheel carried by said shaft, means whereby said wheel may be axially adjusted to secure a desired position of the imprint of the dater head upon said printing cylinder, means normally forcing said links toward said cylinder, means for limiting movement of said links toward said cylinder, a gear carried by said shaft enmeshed with a gear upon said cylinder, means whereby a dater head may be mounted upon said wheel, and an inking roller in engaging relation with the inking mechanism of the plate cylinder and said wheel.

9. A dating attachment for rotary printing machines embodying therein links pivotally mounted adjacent the printing cylinder and the inking mechanism of a plate cylinder co-operating therewith, a shaft mounted in said links, a wheel carried by said shaft, means whereby said wheel may be adjusted circumferentially of said shaft to vary the moment of the making of the imprint from a dater head carried by said wheel upon said printing cylinder, means whereby said wheel may be axially adjusted to secure a desired position of the imprint of the dater head upon said printing cylinder, means normally forcing said links toward said cylinder, means for limiting movement of said links toward said cylinder, a gear carried by said shaft enmeshed with a gear upon said cylinder, means whereby a dater head may be mounted upon said wheel, and an inking roller in engaging relation with the inking mechanism of the plate cylinder and said wheel.

10. A dating attachment for rotary printing machines embodying therein a wheel mounted adjacent the printing cylinder and the inking mechanism of a plate cylinder co-operating therewith, means for rotating said wheel, means whereby a dater head may be mounted upon said wheel, means whereby said wheel may be axially adjusted to secure a desired position of the imprint of the dater head upon said printing cylinder, an inking roller in engaging relation with the inking mechanism of the plate cylinder and said wheel, and means whereby said inking roller may be axially adjusted in conformity with the axial adjustment of said wheel.

11. A dating attachment for rotary printing machines embodying therein a wheel mounted adjacent the printing cylinder and the inking mechanism of a plate cylinder co-operating therewith, means for rotating said wheel, means whereby a dater head may be mounted upon said wheel, a vibrator roll co-operating with a roller of the inking mechanism of the plate cylinder, and an inking roller in engaging relation with said vibrator roll and said wheel.

12. A dating attachment for rotary printing machines embodying therein a wheel mounted adjacent the printing cylinder and

the inking mechanism of a plate cylinder co-operating therewith, means for rotating said wheel, means whereby a dater head may be mounted upon said wheel, a pivotal arm, an inking roller carried thereby, and means operative respectively upon said roller and upon said arm, whereby said roller may be universally adjusted to bring it into proper engaging relation with the inking mechanism of the plate cylinder and said wheel.

13. A dating attachment for rotary printing machines embodying therein a wheel mounted adjacent the printing cylinder and the inking mechanism of a plate cylinder co-operating therewith, means for rotating said wheel, means whereby a dater head may be mounted upon said wheel, means whereby said wheel may be axially adjusted to secure a desired position of the imprint of the dater head upon said printing cylinder, a pivotal arm, an inking roller carried thereby, means operative respectively upon said roller and upon said arm, whereby said roller may be universally adjusted to bring it into proper engaging relation with the inking mechanism of the plate cylinder and said wheel, and means whereby said pivotal arm may be adjusted in conformity with the axial adjustment of said wheel to maintain the proper engaging relation of the inking roller carried by said arm with said wheel.

14. A dating attachment for rotary printing machines embodying therein a wheel mounted adjacent the printing cylinder and the inking mechanism of a plate cylinder co-operating therewith, means for rotating said wheel, means whereby a dater head may be mounted upon said wheel, means whereby said wheel may be axially adjusted to secure a desired position of the imprint of the dater head upon said printing cylinder, a pivotal arm, an inking roller slidably mounted in said arm, an adjusting screw operative upon said roller to impart movement thereto toward or from said wheel, stops upon opposite sides of the point of pivotal support of said arm, an adjusting screw carried by said arm and operative upon one of said stops to impart pivotal movement to said arm toward or from said wheel, and means whereby said arm and said stops respectively may be adjusted in conformity with the axial adjustment of said wheel to maintain the proper engaging relation of the inking roller carried by said arm with said wheel.

15. A dating attachment for rotary printing machines embodying therein links pivotally mounted adjacent the printing cylinder and the inking mechanism of a plate cylinder co-operating therewith, a shaft mounted in said links, a wheel carried by said shaft, means whereby said wheel may be adjusted circumferentially of said shaft to vary the moment of the making of the imprint from a dater head carried by said wheel upon said

printing cylinder, means whereby said wheel may be axially adjusted to secure a desired position of the imprint of the dater head upon said printing cylinder, means normally forcing said links toward said cylinder, means for limiting movement of said links toward said cylinder, a gear carried by said shaft enmeshed with a gear upon said cylinder, means whereby a dater head may be mounted upon said wheel, a pivotal arm, an inking roller slidably mounted in said arm, an adjusting screw operative upon said roller to impart movement thereto toward or from said wheel, stops upon opposite sides of the point of pivotal support of said arm, an adjusting screw carried by said arm and operative upon one of said stops to impart pivotal movement to said arm toward or from said wheel, and means whereby said arm and said stops respectively may be adjusted in conformity with the axial adjustment of said wheel to maintain the proper engaging relation of the inking roller carried by said arm with said wheel.

25 In witness whereof I have hereunto affixed my signature this 28th day of June, 1928.

FRANK C. MARQUARDT.
